No. 825,019.

PATENTED JULY 3, 1906.

E. I. DODDS.
METALLIC CAR CONSTRUCTION.
APPLICATION FILED MAR. 27, 1905.

UNITED STATES PATENT OFFICE.

ETHAN I. DODDS, OF AVALON, PENNSYLVANIA, ASSIGNOR TO THE PULLMAN COMPANY, OF CHICAGO, ILLINOIS, A CORPORATION OF ILLINOIS.

METALLIC CAR CONSTRUCTION.

No. 825,019.

Specification of Letters Patent.

Patented July 3, 1906.

Application filed March 27, 1905. Serial No. 262,390.

To all whom it may concern:

Be it known that I, ETHAN I. DODDS, a citizen of the United States, and a resident of Avalon, county of Allegheny, State of Pennsylvania, have invented certain new and useful Improvements in Metallic Car Construction, of which the following is a specification.

In other applications for Letters Patent of the United States, filed, respectively, on the 10 18th day of June, 1904, and bearing the respective Serial Nos. 213,139 and 213,140, I have shown and described steel car constructions in which the side and end walls of railway-cars are constructed of comparatively 15 small plates, such as can readily be introduced into ordinary furnaces and straightened or restored after being bent or twisted by reason of accident. In the second of the 20 two applications named I have illustrated and described an end construction for steel cars, particularly of the gondola type, in which the car end is made up of two end plates joined by a uniting member of special 25 construction and adaptation. The other application referred to relates to a special car-side construction in which the side plates extend from one side stake to the next and is attached thereto without overlapping.

The present invention relates to a car-end 30 construction wherein three or more end plates are joined by special supporting devices adapted to strengthen the end construction and to simplify the renewal or replacement of the structural elements constituting the 35 end of a car.

It is a common feature of all the inventions concerned in the former and the present applications that the plates constituting the sides or ends, as the case may be, of the car 40 construction are separately removable and replaceable and are easily treated in furnaces of ordinary size and construction, for the purpose of straightening or restoring injured plates without the necessity of removing a large number of rivets or replacing such rivets after the work of repair has been accomplished.

By building up the end of the car from 45 three plates the said plates are small enough to be easily handled, and in case the injury incurred applies to only one of the said plates it is easy to straighten it in a furnace of ordi-

nary size, in which case it is only necessary to remove one set of rivets and restore the plate or replace it by another, whereby considerable labor and expense are avoided. Two of the end plates made use of in the construction described in the present application are secured to the corner member by any appropriate means, while the middle end plate is 60 connected with the aforesaid end plates by means of T-shaped stakes constituting butt-strap as between the central end plate and the side end plate. The stakes referred to extend from the top plates or rails to the 65 draft-sills, the flange of the T tapering from its bottom toward the top of the car. They are thus provided two T-shaped supporting and uniting members, and these members are themselves joined through their projecting 70 flanges by a member which covers the draft-sills and provides a gusset secured to the aforesaid flanges. In this way a strong and substantial end construction is provided for the car, the same being adapted to resist the 75 ordinary strains to which in practice the ends of car-bodies are subjected.

My invention is illustrated in the accompanying drawings, in which—

Figure 1 is an end elevation of a steel car 80 embodying my invention. Fig 2 is a plan sectional view taken along the line 2 2 in Fig. 1. Fig. 3 is a section taken along the line 3 3 in Fig. 2. Fig. 4 is a perspective view of a combined gusset-plate and end covering for 85 the draft-sills, and Figs. 5 and 6 are different modifications of the part shown in Fig. 4.

Referring more particularly to the drawings, 1 1 are the center or draft sills, and 2 2 2 are plates forming the ends of the car-body. 90 Connections with adjacent parts are made by means of angle-pieces 3 3 3 3. The two end plates 2 2 are joined by any suitable means to corner members 4 4, to which are also riveted side plates 5 5, as shown.

At 6 6 I show end stakes or butt-straps and stakes combined, the same extending from the upper plane of the draft-sills 1 1 to the top plate or rail 7. One part of each end stake consists of a flange 8, tapering from the bottom of the stake to the top, as clearly shown in Fig. 3. To the flanges 8 are secured the upright members 9 9 of a gusset 10, which also has a vertical portion 11 and de-

pending and bent-in portions 12 12. The parts 9, 11, and 12 may conveniently be made of one piece of metal.

When the elements above described are all combined and riveted in the manner indicated, the end of the car-body becomes a very strong rigid structure, and at the same time the parts can readily be taken out and replaced when necessary or desirable.

10 Further reinforcement may be given by angular corner-brackets 13 13, preferably of pressed steel, and rolled members 14 14, secured underneath the car-floor. Each of the brackets 13 13 has an integral flange along its two sides adjacent to the side and end of the car, said flange tapering from the central portion upward. The corner member may be made of a piece of channel metal bent backward, as clearly described in my 15 second application referred to above.

The mode of utilizing the modified forms of gusset and sill-covering illustrated in Figs. 4 and 5 is obvious.

This patent is intended to embrace only so much of the disclosure made herein as is covered by the claims. 25

I claim as my invention—

1. In a car having draft-sills, a metallic cover for the projecting ends of the sills and vertical gusset-plates integral therewith. 30
2. As an article of manufacture, a metallic cover for the ends of draft-sills and a set of vertical gusset-plates integral therewith.
3. A car end comprising three or more plates, two or more end stakes forming butt-35 straps for adjacent plates, and each provided with a vertical flange projecting beyond the plates, in combination with one or more gussets connecting adjacent flanges.

Signed at Chicago, in the county of Cook 40 and State of Illinois, this 20th day of March,
A. D. 1905.

ETHAN I. DODDS.
